UNITED STATES PATENT OFFICE

147,776

DESIGN FOR A CRIB TOY OR SIMILAR ARTICLE

Murray M. Backelman, New York, N. Y.

Application May 20, 1946, Serial No. 129,884

Term of patent 14 years

(Cl. D34—15)

To all whom it may concern:

Be it known that I, Murray M. Backelman, a citizen of the United States of America, residing in the Borough of Bronx, city of New York, county of Bronx, and State of New York, have invented a new, original, and ornamental Design for a Crib Toy or Similar Article, of which the following is a specification, reference being had to the accompanying drawing, forming part thereof.

I claim:

The ornamental design for a crib toy or similar article, as shown.

MURRAY M. BACKELMAN.
